UNITED STATES PATENT OFFICE.

GILBERT B. WICKERSHAM, OF PITTSBURGH, PENNSYLVANIA, ASSIGNOR TO DIAMOND FORGING & MANUFACTURING COMPANY, OF PITTSBURGH, PENNSYLVANIA, A CORPORATION OF PENNSYLVANIA.

COMBINED TIE AND LADDER-RUNG MEMBER FOR SILOS AND THE LIKE.

1,229,002.

Specification of Letters Patent.

Patented June 5, 1917.

Application filed October 1, 1914. Serial No. 864,524.

To all whom it may concern:

Be it known that I, GILBERT B. WICKERSHAM, a citizen of the United States, residing at Pittsburgh, in the county of Allegheny and State of Pennsylvania, have invented a new and useful Improvement in Combined Tie and Ladder-Rung Members for Silos and the like, of which the following is a full, clear, and exact description, reference being had to the accompanying drawings, forming part of this specification, in which—

Figure 1 is a sectional plan view of a silo showing my invention applied thereto;

15 Figs. 2 and 3 are plan and side views, respectively, of the combined tie and rung member;

20 Figs. 4 and 5 are detail sectional views illustrating different steps in the manufacture of said member.

My invention has relation to a combined tie and rung member for silos and similar structures, and is designed to provide a device of this character which can be readily 25 and cheaply made and which forms an efficient device for the purpose.

The device is especially designed for use as a tie across the usual door opening of a silo, and is so placed relatively to the structure that a series of superimposed ties, either with or without interposed rung members may be used as a ladder, forming a structural part of the silo.

In the manufacture of the device, I take 35 a piece of hollow metal pipe, such as indicated at 2 in Fig. 4, and insert a plug 3 in each end portion thereof. Each end portion of the pipe back of the plugged portions is then flattened in the manner indicated at 4, 40 this flattening operation leaving the plugged end in the position illustrated in Fig. 4. The plugged end portions are then bent upwardly into a position substantially at right angles to their initial position, as shown in 45 Fig. 5. In this position, the plugged portions form solid projections to which may be attached the metal reinforcements 5, when the tie is embodied in the silo structure.

The numeral 6 designates one layer of the 50 blocks of which the silo is constructed in a well known manner, each of these blocks having a channel 7 in its upper surface to receive the end portions of the tie and also

the metal reinforcements 5. This channel may be filled with cement or mortar, as indicated at 8. 9 designates the door opening on one side of the structure, and 10 the usual doors.

The tie members are bent to conform approximately at their end portions to the 60 general curvature of the structure, and in building up the structure, these ties are inserted at the desired intervals between the courses of tiles or blocks 6, with their bent end portions lying in the channels of the 65 blocks. The reinforces 5 are then attached to the projections formed by the plugged end portions of the ties.

It will be readily seen that the central portions of the ties extend across the door opening outside of the doors 10, in proper position to be utilized as ladder rungs.

Tie members constructed in accordance with my invention can be easily manufactured at a relatively low cost, and can be 75 readily shipped and assembled in the structure as it is built.

One manner in which the device herein described may be utilized in connection with other parts of the silo structure to form a 80 ladder is described and claimed in my co-pending application, Serial No. 864,529, filed October 1, 1914.

I claim:

1. A combined tie and rung member for 85 silos and the like, comprising a piece of metal pipe having plugged end portions bent at an angle to the axis of the pipe to form a circular connecting boss, the cross sectional area of the metal at the end portions being substantially equal to the cross sectional area of the pipe and having flattened portions between said projections and the intermediate portion of the pipe, substantially as described.

2. A combined tie and rung member for 90 silos and the like, comprising a piece of hollow metal pipe having plugs inserted in its end portions and said end portions bent at an angle to the axis of the pipe to form a 100 circular connecting boss, the cross sectional area of the metal at the end portions being substantially equal to the cross sectional area of the pipe and having flattened portions between said projections and the body 105 of the pipe, the end portions of the pipe car-

rying said projections being also bent in a generally curved direction, substantially as described.

3. A combined tie and rung member for silos and the like, comprising a piece of metal pipe having plugged end portions bent at an angle to the axis of the pipe, the cross sectional area of the metal at the end portions being substantially equal to the cross sectional area of the pipe, and having flattened portions between the projections and the intermediate portion of the pipe, said

flattened portions extending under the plugs, and the bottom thereof being approximately flush with the bottom of the central portion, the upper layer of each flattened portion at the ends being bent upon itself underneath the plug; substantially as described.

In testimony whereof, I have hereunto set my hand.

GILBERT B. WICKERSHAM.
